UNITED STATES PATENT OFFICE.

MILTON F. WILLIAMS, OF ST. LOUIS, MISSOURI, ASSIGNOR TO WILLIAMS PATENT CRUSHER & PULVERIZER CO., OF ST. LOUIS, MISSOURI, A CORPORATION OF MISSOURI.

FEED GRINDER.

1,419,089.

Specification of Letters Patent. Patented June 6, 1922.

Application filed April 28, 1919. Serial No. 293,203.

To all whom it may concern:

Be it known that I, MILTON F. WILLIAMS, a citizen of the United States, residing at St. Louis, State of Missouri, have invented 5 certain new and useful Improvements in Feed Grinders, of which the following is a specification.

This invention relates to certain new and useful improvements in feed grinder the 10 peculiarities of which will be herein after described and claimed.

The main object of my invention is the provision of means adapted to break and separate the coarse broken feed from the fine particles; secondly to vary the feed inlet; 15 thirdly to separate the finest particles from the medium ground and fourthly, to provide a special form of stirrup hammer having a special form of cross bar head connecting 20 the spaced shanks.

In grinding chicken feed such as corn, oyster shells and so forth, it is desirable to effect a preliminary breaking or grinding of the feed to coarse particles with little dust 25 and to separate the coarse from the finest particles, and then to grind the coarse balance to medium particles as hereinafter described.

In the accompanying drawing on which 30 like reference letters indicate corresponding parts, Fig. 1 represents a vertical sectional elevation of a machine embodying my invention,—the section being taken near the center and across the shaft of the rotor; 35 Fig. 2, a front view of the same with portions of the hopper broken away to show the adjustable slide, and other parts of the casing broken away to show the breaker plate and cage; Fig. 3, a face view of a modified 40 form of breaker plate from that shown in Figs. 1 and 2; Fig. 4, a vertical section of said plate on the line 2—2 of Fig. 3; and Fig. 5, a similar sectional view on the line 3—3 of Fig. 3.

45 The letter A designates a rotor shaft on which is mounted pivoted hammers of the kind having two shanks spaced apart and pivoted at their inner ends eccentric to the shaft and connected at their outer ends by 50 a cross bar head. B co-operating with a cage C of perforated metal, or other suitable design, mounted in a suitable casing D surrounding and enclosing the rotor, and having a feed hopper E comprising an in-

clined front wall F and an opposite wall G 55 converging downward toward the front wall. A pocket is formed in the casing below the feed hopper by a wall H behind a breaker plate, the front face of which plate is in line with the inclined wall F of the feed hopper. 60 The said casing is preferably open at the sides opposite this pocket for the breaker plate, so that the said breaker plate may be inserted sideways into said pocket and rest against said wall H.

65 This breaker plate is hollow and has a perforate front face I with backwardly extending rib J at the top, and side ribs K, which latter close the openings in the side of the casing when the breaker plate is in 70 its located position, and form, together with the casing wall H, a chamber back of the perforate face for the reception of the coarser particles of the feed that pass the openings L in said face. A frame is thus 75 formed supporting the front face and open at the bottom for the discharge of the particles entering said chamber. Below the pocket is a passage M communicating with the chamber of the breaker plate and separated from the balance of the material discharged through the cage C, by a partition 80 wall N or other suitable means. The openings L in the breaker plate are of different size, preferably larger, than the openings in 85 the cage C. The feed material suffers a preliminary breaking upon the breaker plate and a large proportion of it passes through the openings L into the discharge passage 90 M communicating with the chamber of the breaker plate.

A certain amount of fine particles and dust is necessarily formed in this preliminary grinding, and such fine particles are separated from the coarse particles, preferably 95 by means of a pipe O intersecting said passage M and subject to air suction by means of an exhaust fan (not shown). The feed from the hollow breaker plate falls past the intersection of the pipe O with the discharge 100 passage, and the suction of the air draws out the finest particles as indicated by the arrow in Fig. 1, while the coarse particles continue onward to a suitable compartment for storage.

In Figs. 1 and 2, I have shown a hollow breaker plate with a smooth face and perforations therein, such as a plate steel face

fastened by screws or otherwise to the supporting frame. In Figs. 3, 4 and 5, I have shown a modified breaker plate in which the perforations L' are provided with guiding and deflecting angular projections, preferably formed by a front face P inclined outward and upward from the face of the plate and ending in a point of maximum projection between the converging upwardly inclined sides of the projection. The point of said projection is preferably concave as shown in Fig. 3 and directly adjacent and below the hole L', so that the preliminary breaking effected by said projections in conjunction with the hammers will facilitate the discharge of the particles through the respective holes L'. The sides of the angular projection guide the broken particles that do not enter the adjacent hole, to the lower hole adjacent. The said holes are preferably alternately disposed in horizontal rows with the angular projections, and also alternate in vertical rows, as shown in Fig. 3.

The preferred style of pivoted hammer to co-operate with this perforated breaker plate, is that shown in Fig. 1, in which the outer surface of each hammer B is part of a cylinder the center of which is the pivot on which the hammer is mounted parallel to the shaft A. The circular width of the head of the hammer is substantially the length of the hammer from the pivot to the outer cylindrical surface, so that each hammer constitutes part of a jaw roller, and some element of this outer surface is always in close proximity to the cage or breaker plate when opposite. The inner face of each head is a plane as shown, or otherwise formed to intersect at a sharp angle the forward and rear edges of the cylindrical outer surface of the head, and thereby constitute a sharp cutting edge adapted to pass easily through the material being reduced in the rotor chamber, and cut the same. The cylindrical outer face of each hammer, being curved on a shorter radius than the cage, normally forms a decreasing throat from the front edge of the hammer to that element in the face of the head that is nearest to the cage, and when the material enters this throat it retards the hammer and causes the head to roll backward about its pivot and thus bring its forward edge nearer to the cage. This jaw-rolling movement diminishes the size of the throat as the front edge rolls back closer to the cage and tends to crush with a jaw-closing action, any material engaged by the throat of the hammer. When the hammer is operating opposite the perforated breaker plate, this crushing roller-jaw action forces the material through the perforations in said plate. The projections on the breaker plate shown in Figs. 3, 4 and 5, assist the roller acting hammer base in reducing the material, and the concave tops of said pro-

jections guide the crushed particles through the adjacent openings like spouts directing the material to the openings. In co-operation with the cage, the rolling outer surfaces of said hammers first crush and then force the material through the openings in the cage.

The walls of the casing are extended upward at D' above a partition wall d substantially in line with the cage C which forms an outlet opening 6 opposite the feed hopper, for the material being ground in said cage. Through this back opening the hammers discharge some of the material and any foreign metal that may enter with the feed, into the chamber between the walls D' and d which constitute a metal catcher above the rotor. At the side or elsewhere in the casing, an opening 7 is provided connecting to a pipe 8 under air suction, in order to draw off the finest particles as indicated in Fig. 1. Between the metal catcher and the hopper and above the rotor, the casing walls form a chamber 9 for arresting the dust formed in the grinding operation on the cage below. This chamber is entirely closed except at the bottom and the forward edge of the opening is formed by the thickened bottom end of the wall G.

The outer convex surface of the pivoted hammer B is struck from a center substantially the center of the pivot of each hammer, and is eccentric to the grinding surface of the cage and thus exerts a crushing action upon the material interposed between the outer convex surface of the hammers and the concave surface of a larger radius of the cage, as well as the flat inclined surface of the perforated breaker plate. The inner surface of each hammer is practically a straight face transverse to the shanks and therefore the plane of the inner face cuts the convexed outer face at the front and the rear of each hammer and forms sharp front and rear edges, capable of being reversed when one edge is dulled and a new edge is desired. The sharp edges of each bilateral and reversible head pass through the material being reduced with little obstruction, as the radial thickness between the front and rear edges is relatively small compared with the width from front to rear edge. Thus the material that is not caught between the convex outer face of the hammer and the concave face of the cage will be divided by the sharp edge of each hammer and flow past the hammer on the inner side of the head and be caught by the next succeeding hammer and subjected to the crushing grinding action exerted by the pivoted hammer with outer cylindrical face disposed eccentric to the grinding surface of the cage.

I claim:

1. A feed grinder comprising a breaker plate, having on its face rows of alternating

holes and angular projections,—said projections having three sides converging upward to a blunt point at its maximum projection that is located below the respective hole in 5 the row above, and a casing having walls forming a chamber behind and shut in by said breaker plate, substantially as described.

2. A feed grinder comprising a breaker 10 plate, having angular projections inclining upward and outward from its face and having sides converging upward and ending in a point of maximum projection with a concave upper face, and holes respectively 15 located above said projections and coinciding with the concave tops, and casing walls forming a chamber behind said breaker plate, whereby the material broken on said projections is directed through said openings into said chamber, substantially as described.

3. A feed grinder comprising rotary hammers, a perforated breaker plate having its lower edge located in the path of the hammers, an adjacent cage co-acting with said 25 hammers, and a casing for said breaker plate, hammers and cage, and having a discharge outlet below the breaker plate and having walls forming a communicating 30 chamber behind said breaker plate, and forming also a partition for said discharge outlet adapted to separate the material passing through said breaker plate after being ground thereon, from that passing through 35 said cage substantially as described.

4. A grinder comprising a casing, a breaker plate, a cage, and a rotor in said casing having pivoted hammers each consisting of shanks spaced apart and pivoted eccentric to 40 the axis of the rotor at their inner ends and connected at their outer ends by a cross bar head the outer cylindrical surface of which is struck from the pivotal center of said hammer and acts like a jaw roller upon the material 45 being ground in the throat formed by the forward portion of said hammer and the adjacent cage and breaker plate, and the inner surface between said shanks meeting the outer surface in acute angles at front 50 and rear forming sharp cutting edges throughout the entire length of said head.

5. A feed grinder comprising a casing having a wall at the front opposite a breaker plate forming a pocket, and a partition wall 55 below the breaker plate, another lower portion of the front wall parallel to said partition wall and forming a discharge passage communicating with said pocket,—a hollow breaker plate having a perforate face extending across said pocket above said discharge passage, and a pipe connected to an

opening in said lower front wall and communicating with said passage.

6. A feed grinder comprising a rotor, a cage, a perforated hollow breaker plate having its lower end lying in the path of said rotor, and a casing for said rotor and breaker plate having a portion of its walls at the front adjacent to the breaker plate, and a partition wall parallel and adjacent to the front wall and below the breaker plate and forming a discharge passage leading from said breaker plate,—said casing also having walls at the top and back which, together with an adjacent partition wall concentric 75 with the rotor, form a metal catcher above said rotor,—said discharge passage and metal catcher having outlet openings adapted for connection to suction means.

7. A grinder comprising a casing, including a cylindrical grinding surface, a shaft, hammer supports mounted on said shaft, and hammers consisting of shanks spaced apart the width of the grinding surface and pivotally mounted by their inner ends on 80 said supports, and each connected at their outer ends by a cross bar head the outer surface of which is convex and disposed eccentrically to the grinding surface of the cage, the forward portion of each head terminating 85 in an acute angle forming a sharp edge which extends throughout the length of the head.

8. A grinder comprising a casing including a cylindrical grinding surface, a shaft, pivoted hammers operatively mounted on said shaft, each of said hammers terminating at its free end in a head the outer surface of which is convexed and disposed eccentrically to the grinding surface of the 90 cage, and each head being bilateral with outer and inner faces that form sharp front and rear edges parallel to the shaft,—said edges being reversible.

9. A grinder comprising rotary pivoted 100 hammers each having a head the outer surface of which is a cylindrical plane struck from substantially the pivot point as a center, and the inner face of the head being substantially a plain flat face that intersects the outer convex face in a sharp edge at the front and rear parallel to the pivotal axis,—the radial thickness midway between front and rear edges being relatively small compared to the width between said edges so as 110 to adapt the long sharp-edged head to pass through the material being reduced with relatively small resistance.

In testimony whereof I have affixed my signature.

MILTON F. WILLIAMS.
